DRY CLEANING MACHINE

Sidney Stribling, San Francisco, Calif.

Application August 21, 1944, Serial No. 550,356

1 Claim. (Cl. 68—18)

1

This invention relates to a machine and method of dry cleaning and more particularly to means and methods for dry cleaning wearing apparel, fabrics and the like.

Among the objects of the invention is the simplification of the equipment and method of dry cleaning.

Another object is to reduce the dry cleaning and cleaning fluid salvaging apparatus to the minimum, with a fluid circulating means combined therewith.

Another object is the introduction of controlled heating units in the washer and salvaging apparatus.

Another object is to enable the selective use of a variety of cleaning fluids in a single washing cycle.

Another object is to provide a single fluid clarifying and salvaging unit adapted to a variety of cleaning fluids.

Other objects and advantages will appear as the description proceeds. In the specification and the accompanying drawings the invention is disclosed in its preferred form. But it is to be understood that it is not limited to this form. Because it may be embodied in modifications within the spirit of the invention as defined in the claim following the description.

Heretofore it has been the practice to separate the dry cleaning washer from the fluid salvaging or redistilling apparatus and to centrifuge the cleaned garments in a separate machine. A modern equipment usually comprises as many as five separate machines, requiring excessive floor space and rehandling of the garments being cleaned. The present invention requires the minimum of floor space and but two handlings of the garments, to load then unload the rotary washer.

In the one sheet of drawings:

Fig. 1 is a side elevation of a tumbling drum washer unit in full lines, combined with a redistillation unit, shown in vertical section, in accordance with this invention.

Fig. 2 is a vertical section of a tumbling drum washer shown in Fig. 1, on the line 2—2.

Fig. 3 is a vertical section of one of the filtering units shown in Fig. 1.

In detail the structure shown in Fig. 2, comprises the base 1, adapted to be mounted upon the floor, and surrounded by the cylindrical splash wall 2. This base has the bearing pillars 3, 4, integral with the base and having the bearings 5, 6 on their top portions.

The external tilting drum 7 has the trunnions

2

8, 9, mounted in the bearings 5, 6. This drum is held in the vertical position shown by the spring latch 10 pivoted on the base and controlled by the manual link 11 guided in the wall 2. It is held in the horizontal position by the spring catch 12, pivoted on the wall 2 and manually controlled by the link 13 guided in the wall adjacent the link 11, for convenience. The hand lever 14 is fixed in the trunnion 8 for swinging the tilting drum 7 into the vertical or horizontal positions, the latter being indicated by dot-dash lines. The drum is provided with the removable pressure tight cover 15.

The perforated tumbling drum 16 is mounted 15 within the tilting drum on the step shaft at 17 and the driving shaft 18 mounted on its opposite ends and engaging bearings arranged in the opposite ends of the tilting drum respectively. The shaft 18 passes through the stuffing box 19, for 20 sealing the contents of the tilting drum. The tumbling drum has the removable pressure tight cover 20, of smaller diameter and adapted to be alined with the cover 15 on the tilting drum.

The shaft 18 has the pulleys 21, 22 fixed thereon 25 and driven by the belts 23, 24 driven by pulleys on the shaft of the change speed gear box 25 which has the control handle 26, by which the tumbling drum may be driven at speeds selected by the handle 26. The shaft in the change speed 30 gear box is driven by the motor 27 mounted upon the outside of the tilting drum 7. In this manner the tumbling drum 16 may be driven at relatively low speed in the horizontal position, during the cleansing or washing cycle and at high speed for 35 centrifuging the contents of the tumble drum free of the fluid, when the tilting drum is in the vertical position.

The clarifier comprises the pressure tight tank 28, having a series of spiral steam pipes arranged 40 therein about midway of its height and having the steam inlet and outlet valves 29, 30 respectively, controlling the steam supply from any suitable source, not shown.

A similar heating unit is located adjacent the 45 bottom of the clarifier and controlled by the inlet and outlet steam valves 31, 32. The tank 28 has the lower drain valve 33, through a filter 34 located on the bottom of this tank. The pressure tight sludge removal door 35 is provided at the 50 bottom of this tank. A bank of filter units at 36 are arranged in the upper portion and suspended from the removable cover 31.

These filter units 36 discharge through independent valves and sight glasses such as 38, 39 55 and into the manifold 40, that is connected

through the pipe 41 and valves 42, 43 with the fluid storage tank 44. This tank may be one of several connected through the pipe 41 with the clarifying unit, through independent valves and adapted to contain a variety of cleaning solutions respectively.

The conventional condenser comprises the water jacket 45, having a condensing worm 45' therein, connected through the pipe 46 and valve 47, with the top of the clarifier tank 28 to receive and condense vapor therefrom. The worm discharges at the bottom through pipe 48, leading to a container for the condensation, or back to the tank 44. Water is introduced into the water jacket 45 through the inlet 49. An outlet from the water jacket is connected through the valve 50, with the top of the tank 28.

The cleaning fluid supply from a source such as 44, discharges through the pipe 41, the valve 51 and the flexible hose 52 into the tilting drum 7. From this drum the fluid gravitates through the flexible hose 53, the pipe 54 and into the intake of the pump 55, which discharges it through the pipe 56 and the valve 57 into the top of the tank 28, maintaining a pump pressure on this tank that forces the fluid therein outward through the filters at 36, the pipe 41, the valves 42, 51 and back into the tilting drum 7 when the valve 43 is closed.

During the washing cycle, a circulation of heated fluid under pump pressure is maintained in the washing and clarifying units 7, 28. To assure the maintenance of the desired temperature throughout the circulating system described, especially in the drum 7, it is also provided with an internal heating unit comprising a spiral pipe having the steam inlet and outlet 58, 59 respectively.

The soilure from the garments or other contents of the tumble drum 16 is mechanically removed by the filters at 36, and is precipitated as sludge into the lower portion of the tank 28, where it remains inert and separated from the fluid circulated by the pump 55. These filter units as shown in Fig. 3, comprise the center pipe 60, open at the end. This is surrounded by the wire mesh cage 61, covered by a suitable fabric filter pad 62, through which the fluid seeps, leaving the sludge on its outside, from which it precipitates to the bottom of the tank.

This invention is adapted to the use of any conventional cleansing fluids such as hydrocarbon derivatives, carbon tetrachloride, saponaceous solutions and mixtures thereof, miscible or nonmiscible. One advantage of the present invention and its mode of operation, is the fact that one form of cleaning fluid may be introduced and withdrawn and another or others substituted, during the cleaning cycle, without shutting down, transferring the garments being cleaned, or opening the washing unit at 7, or the clarifier at 28.

The mode of operation is substantially as follows: The selected cleaning fluid is introduced, for instance from the storage tank 44, through the valves 43, 51, the flexible hose 52 and into the tilting drum 7. The pump 55 is then started, with the tilting tank in the horizontal position and previously loaded with the garments to be cleaned, through the doors 15, 20. The quantity of fluid in the tank 7 is regulated by the valve 51, to the desired level, usually about one third full, so that the garments will rise, fall and splash into the liquid in the tumble drum 16,

rather than to float in an excess of fluid. The intake of fluid through the valve 51 is proportioned to the capacity of the pump 55, which withdraws the fluid from the drum 7 and discharges it into the clarifier unit 28. This builds up a pressure within the clarifier which ejects the fluid therefrom, through the bank of filters at 36, into the pipe 41, through the open valves 42, 51 and back to the washer at 7. A rapid circulation of warm clean fluid is maintained under pressure during the washing cycle. The desired temperature of the fluid is regulated by the heating units at 29, 31, 58, as indicated on the thermometer 63.

When the sludge has collected in the lower portion of the tank 28 to a fluid contaminating extent, the valve at 64 is opened and the usable liquid above is drawn off and returned to the storage tank such as 44. The sludge is then withdrawn through the door 35.

When the sludge is removed, the clarifier may then be used for purifying the contaminated liquid in the tank 44. This is done by again pumping the liquid from the tank 44, through the tilting drum and back into the desludged clarifier tank 28, until it rises above the heating unit 29-36. The heat liberated in the clarifier tank 28 causes vapors to rise from the volatile contents and pass out through the outlet 46, the valve 47, the worm 45' to the outlet 48 from whence the condensed fluid is returned to the tank 44 for reuse. The worm 45' is chilled by water circulating through the water jacket 45, from the inlet 49.

Should the temperature rise above the desired degree and cause a too rapid vaporization, this can be checked by opening the valve 59 which will inject cold water into the tank 28 and cause a drop of temperature therein. This water will form a film on top of heavier fluids, such as carbon tetrachloride, or descend through the lighter fluids and drop into the sludge sump at the bottom of the tank 28, where it can be withdrawn through the drain valve 33. The volatiles in the sludge are vaporized by the heating unit at 31, 32 and rise into the liquid above.

The washer operates substantially as follows: The latch 10 is released and the drum 7 swung to the horizontal position by the handle 14. In this position the latch 12 automatically engages to hold the drum in the horizontal position.

The cover 15 is then removed and the tumble drum 16 manually rotated until its cover 20 registers with the opening beneath the cover 15. The removal of the cover 20 permits free access to the interior of the tumble drum, which is then loaded with the garments to be cleaned. The covers 15, 20 are then replaced and the drum 7 is filled to the desired height to saturate the garments with the cleaning fluid flowing from the tank 44 through the flexible hose 52.

The motor 27 is then switched on and the tumble drum 16 is driven through the reduced speed pulley 22, until the contents of the washer is thoroughly cleaned by the rotary, splashing and agitation of the cleaning fluid circulating through the perforated wall of the tumble drum.

When the cleaning cycle is completed, the pump 55 sucks the cleaning fluid from the drum 7 and discharges it back into the clarifier tank 28. The latch 12 is then released and the drum 7 restored to the vertical position and driven at a centrifuging speed by the smaller pulley 22 by

the motor 21. This removes the cleaning fluid absorbed by the contents of the tumble drum 16, which accumulates in the drum 1 out of contact with the contents of the tumble drum. Any excess of extracted fluid may be pumped out as described.

The tilting drum 1 is then restored to the horizontal position and the covers 15, 20 removed for unloading the tumble drum 16. A particular advantage of the present invention and mode of operation is, that the dry cleaned material is dry when manually handled, greatly reducing the hazards incidental to handling inflammable materials and contaminating vapors. Another advantage is the ease with which a variety of hydro carbon, soapy solutions and various cleaning mixtures, may be interposed and substituted during the cleaning cycle, without opening the various units in the combined washing and clarifying combination of elements. In this manner soapy or detergent solutions may precede or follow dry cleaning fluids, and be washed out with clean water and extracted. The heating element 58, 59 also provide means for raising the temperature to the boiling point if necessary in using water and appropriate solutions in the washer unit.

Having thus described this invention and its mode of operation, what is claimed and desired to secure by Letters Patent is:

A dry cleaning machine comprising a mechanical washer having an enclosing drum; a storage tank for a cleaning fluid and discharging into said enclosing drum; a pressure sealed

clarifier tank having an internal heating element; a filter in said clarifier tank and discharging into said storage tank; a condenser to receive and condense vapors from said clarifier tank and surrounded by a water jacket discharging water into said clarifier tank; and a pump connected with said washer enclosing drum and discharging into said clarifier tank.
